UNITED STATES PATENT OFFICE.

FRANCIS W. GIBSON, OF WEST ROXBURY, AND CLARENCE S. MARDEN, OF CAMBRIDGE,
MASSACHUSETTS, ASSIGNORS TO H. D. BEACH COMPANY, A CORPORATION.

DISPLAY-RACK.

1,082,078.

Specification of Letters Patent. Patented Dec. 23, 1913.

Application filed April 21, 1913. Serial No. 762,489.

To all whom it may concern:

Be it known that we, FRANCIS W. GIBSON and CLARENCE S. MARDEN, citizens of the United States, residing at West Roxbury, county of Suffolk, Commonwealth of Massachusetts, and Cambridge, county of Middlesex, Commonwealth of Massachusetts, have invented certain new and useful Improvements in Display-Racks, of which 10 the following is a specification.

This invention relates to display racks and particularly to an advertising display rack in which boxed goods are displayed for sale. The display of boxed goods calls for a rack which will permit the display of the advertising matter on the goods to the best advantage. Much difficulty has been experienced in finding a rack capable of such advertising display and which at the same time will afford ready access to the goods to be vended, while effectively protecting them against deterioration when being displayed. A further end sought is the production of 25 a rack of this character simple in construction and capable of manufacture at a low figure.

To the end therefore of producing such a device we have devised our present invention.

Our display rack is particularly adapted 30 for the display of such boxed articles as cigars. Cigar boxes usually bear upon the inner face of the cover an artistic label denoting the brand of cigars. The value of this label as a selling medium is well recognized by dealers and usually it is displayed by throwing back the box cover. This not only exposes the cigars to the drying effect of the air, but moreover is an extremely un- 35 sanitary method. To protect the cigars from depreciation and at the same time comply with the law which requires the label on the box cover to be displayed, we provide a display rack having a hinged display. 40 cover transparently covering the cigars and a support to hold the box cover in erect position and to expose its label through an opening therein.

The construction and use of our display 45 rack will be more fully disclosed in the specification which follows, and in the drawings which form a part of that specification we have shown an illustrative embodiment 50 which has been found well adapted to practical use and the requirements of the trade.

Throughout specification and drawings like reference numerals are employed to indicate corresponding parts, and in these drawings: Figure 1 is a front elevation of a display rack in accordance with my invention, and showing a box of cigars displayed therein, Fig. 2 is a vertical section on the line 2--2 of Fig. 1, Fig. 3 is a rear elevation of the rack, the cigar box being removed, and Figs. 4 and 5 are detail sections 60 on the lines 4--4 and 5--5, respectively, of Fig. 1.

The rack thus illustrated is preferably made from a sheet of suitable material. The blank from which it is formed consists 70 of a front member 1 of the desired shape and proportions. This area may be suitably ornamented as shown and may bear any desired advertising matter. A display opening 2 is formed in said wall and is substantially coextensive with the delivery opening of the cigar box 3, which is supported behind said opening in a manner soon to be described. Narrow marginal bearing flanges 4 are left along the top and side edges of the opening and the bottom edge is turned down as indicated at 5 and pressed against the rear face of the front wall to provide a smooth edge which will not cut the fingers in manipulating the 80 transparent cover for said opening. Said cover consists of an open rectangular frame 6, which bears upon the flanges 4 when in closed position and slightly overlaps them. This frame has a display opening 7 registering with but slightly smaller than the opening 2. Both openings are covered by a transparent plate 8 held to the frame on three sides by locking strips 9 and on the rear edge by locking lips 10 turned up from 90 the metal of the cover. These locking strips are made independently of the cover and are held thereto by the inturned flanges 11 thereof. Said flanges in addition provide smooth grasping edges for the fingers in 95 opening the cover. The free ends of the locking strips are formed as edge receiving recesses 12 in which the transparent plate 8 is inserted by a movement transversely of the cover.

The edge of the cover adjacent the locking lips 10 does not have an inturned flange 11 but has the metal turned down as indicated at 13 to engage over a hinge rod 14, the ends of which are fastened to the front 100

105

110

member 1 by clips 15 inserted through suitable slots in said member with their free ends turned away from each other and pressed against the rear face of said member as shown in Fig. 5. A tab 16 is struck up from the metal of the bottom edge of the cover to provide a grasping portion for the fingers in swinging said cover on the hinge thus formed.

10 Upon the sides of the blank are formed side forming areas 16¹ adapted to be bent back at right angles to the front area 1. Upon these areas 16¹ and toward the base thereof are formed supporting areas 17 in the nature of wings which act as an easel back and hold the rack in a position slightly inclined from the vertical. Across the bottom edges of the areas 16¹ and 17 flanges 18 are turned in to provide supporting bearings for the 20 bottom wall of the cigar box. These flanges are depressed as indicated at 19 to form supporting portions spacing the rack from the show case or other support. The box is guided and supported in position behind 25 the registering display openings by lateral bearing flanges 20 turned in from the wings at right angles thereto and lying in a plane substantially parallel to the front area 1. The cover 21 of the cigar box is held by the 30 spring of its hinge in the position shown in Fig. 2, in which position its label is directly behind a second display opening 22 formed in the front area. From this construction it will be seen that the box is held 35 in a position slightly inclined from the vertical by the side and bottom flanges 18 and 20. This positions the cigars behind the 40 transparently covered display openings 2 and 7, respectively, of the front area and cover, and the label on the cigar box cover behind the display opening 22 of said front area.

In use, whenever it is desired to have access to the cigars, the transparent cover is 45 raised by means of the grasping tab 16 and swung back against the upper portion of the front wall where it will stay until returned to covering position owing to the 50 fact that said front area is inclined out of the perpendicular.

The spaces on the front wall left after the display openings have been cut out may be utilized to bear any suitable advertising

matter as may the side forming areas and wings.

Various modifications in the form and arrangement of our display rack may obviously be resorted to if within the limits of the appended claims.

What we, therefore, claim and desire to obtain by Letters Patent is:

1. A sheet metal display rack for boxes of packaged articles comprising a front member having a suitably proportioned display opening therein, said opening being 65 surrounded by edges of the metal of the front to form containing flanges for the same, lateral wing pieces on the lateral edges of said front bent back at substantially right angles thereto, and bearing 70 flanges struck up from said wing pieces and disposed parallel to said front member for supporting the container behind said display opening of the front member.

2. A display rack for a container having a hinged lid comprising a front member having two display openings therein, a transparent cover removably mounted on one of said openings and normally registering therewith, side members integral with said front member and disposed at substantially right angles thereto, and supporting flanges bent up from the side members adapted to hold a container in alignment with said covered opening and with the interior of 85 the container lid against the other display opening.

3. A display rack for a container having a hinged lid comprising a front member having a delivery opening and a lid display opening, integral lateral wings on the edges of said front member providing an easel back for the rack, the lower edges of said wings being turned to provide bearing flanges adapted to hold a container 90 against said front and wing members in alignment with the delivery opening and with the interior of the container lid against the display opening.

In testimony whereof we affix our signatures in presence of two witnesses:

FRANCIS W. GIBSON.
CLARENCE S. MARDEN.
